United States Patent Office

Des. 226,743

Patented Apr. 17, 1973

226,743

TOTE BAG

Robert M. Lee, New York, N.Y., assignor to Hunting
World Incorporated, New York, N.Y.

Filed Jan. 10, 1972, Ser. No. 216,868

Term of patent 14 years

Int. Cl. D3—01

U.S. CL. D87—3 F

FIG. 1.

FIG. 2.

FIG. 3.

FIG. 4.

FIG. 5.

FIG. 6.

FIG. 7.

FIG. 8.

FIG. 9.

FIG. 1 is a perspective view of a tote bag showing my new design;

FIG. 2 is a rear elevational view thereof;

FIG. 3 is a side elevational view;

FIG. 4 is a side elevational view of the side opposite that shown in FIG. 3;

FIG. 5 is a top plan view;

FIG. 6 is a bottom plan view;

FIG. 7 is a perspective view of the tote bag shown in FIG. 1 in a collapsed and closed condition;

FIG. 8 is an end view thereof taken from the right of FIG. 7;

FIG. 9 is a top plan view thereof; and

FIG. 10 is a bottom plan view thereof on a reduced scale.

I claim:

The ornamental design for a tote bag, as shown.
